US0D1095845S

(12) **United States Design Patent** (10) Patent No.: **US D1,095,845 S**
(45) Date of Patent: ** Sep. 30, 2025

(54) **INSTRUMENT HANDLE**

(71) Applicant: **Auris Health, Inc.**, Redwood City, CA (US)

(72) Inventors: **Jonathan Mendoza**, San Francisco, CA (US); **Frankie Vazquez**, San Francisco, CA (US); **Toby A. Stopper**, San Francisco, CA (US); **Wonbin Choi**, San Francisco, CA (US)

(73) Assignee: **Auris Health, Inc.**, Redwood City, CA (US)

(**) Term: **15 Years**

(21) Appl. No.: **29/908,783**

(22) Filed: **Jan. 15, 2024**

Related U.S. Application Data

(62) Division of application No. 29/756,561, filed on Oct. 29, 2020, now Pat. No. Des. 1,015,541, which is a division of application No. 29/634,023, filed on Jan. 17, 2018, now Pat. No. Des. 901,694.

(51) **LOC (15) Cl.** **24-02**

(57) **CLAIM**

The ornamental design for an instrument handle, as shown and described.

DESCRIPTION

FIG. 1 is a bottom, front, left perspective view of an instrument handle;

FIG. 2 is a left-side view of the instrument handle;

FIG. 3 is a right-side view of the instrument handle;

FIG. 4 is a front view of the instrument handle;

FIG. 5 is a rear view of the instrument handle;

FIG. 6 is a top view of the instrument handle; and,

FIG. 7 is a bottom view of the instrument handle.

In the drawings, the broken lines illustrate portions of the instrument handle and form no part of the claimed design.

1 Claim, 4 Drawing Sheets
